W. J. KUHLS.

LOCK.

APPLICATION FILED DEC. 20, 1918.

1,311,606.

Patented July 29, 1919.

UNITED STATES PATENT OFFICE.

WILLIAM J. KUHLS, OF DAYTON, OHIO.

LOCK.

1,311,606.

Specification of Letters Patent. Patented July 29, 1919.

Application filed December 20, 1918. Serial No. 267,617.

To all whom it may concern:

Be it known that I, WILLIAM J. KUHLS, a citizen of the United States, residing at Dayton, in the county of Montgomery and 5 State of Ohio, have invented certain new and useful Improvements in Locks, of which the following is a specification.

My invention relates to locking devices, and more particularly to compensating locks 10 for automobile hoods or for analogous purposes.

The object of the invention is to simplify the structure as well as the means and mode 15 of operation of such devices, whereby they will not only be cheapened in construction, but will be more efficient in use, uniform in action, easily locked and unlocked, and unlikely to get out of repair.

A further object of the invention is to provide 20 a lock mechanism to be located within the hood or other structure, which will thereby be concealed from view.

A further object is to provide a yielding locking device which will automatically 25 compensate for irregularities of manufacture or application, and which will automatically take up any play or lost motion of the interlocked parts, thereby obviating rattle and chatter.

With the above primary and other incidental objects in view as will more fully appear in the specification, the invention consists of the features of construction, the parts and combinations thereof and the mode 35 of operation, or their equivalents, as herein-after described and set forth in the claims.

Referring to the drawings, Figure 1 is a perspective view of the locking device, viewed from the inside of the hood, with a 40 portion of the mounting broken away. Fig. 2 is a vertical sectional view of the assembled apparatus. Fig. 3 is a detail elevation of the inner or rear side thereof. Fig. 4 is a detail view of a modification.

Like parts are indicated by similar characters of reference throughout the several views.

In the drawings, 1 is the hood of the automobile, or the side of the other housing to be locked, while 2 is the hood sill to which 50 the hood or housing is to be engaged.

The locking device comprises a circular recessed casing 3 inserted through a suitably located opening in the hood wall 1 and having a marginal flange 4 bearing against the 55 outer side of the wall 1. Revolvably located within the casing 3 is a disk 5 carrying the handle 6. The disk 5 is journaled upon an integral stud or trunnion 7 engaging in a bearing collar 8 formed in the rear wall of 60 the casing 3. The stud or trunnion projects beyond the casing 3 and is shouldered or reduced to receive a crank arm 9. Loosely mounted in the free end of the crank arm 9 is a wrist pin 10. The wrist pin 10 is 65 formed with a head 11, and is inserted in a counter bored hole in the crank arm from the side next to the casing, whereby the casing prevents the disengagement of the pin when the parts are assembled. The pin 10 70 is free to rotate in the crank arm. The crank is pinned or otherwise fixedly secured upon the reduced end of the stud or trunnion 7.

Inclosing the crank arm and adjacent parts is a semicircular housing like head 12 75 of a pendant bracket arm 13. The head of the bracket is flanged as at 14 and is secured to the casing 3 by rivets 15 or by other suitable means. To the lower end of the bracket arm 13 there is pivoted a locking 80 lever 16 the free end of which is adapted to engage beneath the hood sill 2 or preferably beneath a lug 17 secured to the sill. A helical tensioned spring 18 is connected at one end to the locking lever 16 and at its 85 upper end it is engaged with the wrist pin 10. As shown in Figs. 1 and 2 it is threaded through an eye or opening in the wrist pin, which necessitates the rotation of the wrist pin as the crank is turned. This mode 90 of attachment insures the spring against accidental disengagement. However, an alternative construction is shown in Fig. 4 in which an eye turned in the extended end of

the spring is engaged in a peripheral groove in the pin 10. In this instance the pin may be fixed in the crank.

Upon rotation of the crank to a pendant position as shown in Fig. 3 the tension of the spring 18 is relaxed and the arm 16 is permitted to drop away from the lug 17 and so release the hood. Upon a reversal of the handle by which the crank is turned to an elevated position as shown in Figs. 1 and 2 and by dotted lines in Fig. 3, the arm 16 is again drawn upward into locking engagement beneath the lug 17 and the spring 18 is placed under tension. The spring 18 will yield to compensate for any variations of adjustment, and serves to maintain a constant tension upon the locking arm 16 by which any slack or lost motion of the hood is automatically taken up.

The spring is maintained in tensioned condition and the locking arm in engagement with the lug by turning the crank arm 9 slightly beyond dead center whereupon a stud or lug 19 upon the inner face of the disk 5 engages a stop or lug 20 on the inner face of the casing wall, as shown in Figs. 2 and 3 thereby arresting the disk and crank arm, which are yieldingly held in this position by the spring. In the drawing the stop lug 20 has been shown as a depression in the wall of the casing 3. This however is a matter of convenience of manufacture, and may be varied.

From the above description it will be apparent that there is thus provided a device of the character described, possessing the particular features of advantage before enumerated as desirable, but which obviously is susceptible of modification in its form, proportions, detail construction, and arrangement of parts, without departing from the principle involved, or sacrificing any of its advantages.

While in order to comply with the statute the invention has been described in language more or less specific as to certain structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described my invention I claim:

1. The combination with two relatively movable members to be interengaged, of a locking lever carried by one member and movable into and out of engagement with the other member, a revolute actuating member and a resilient link eccentrically connected with the revolute actuating mem-

ber at one end and engaged with the locking lever at its opposite end, said resilient link being placed under tension to retain the lever in locking position by the rotation of the actuating member.

2. The combination with two relatively movable members to be interengaged, of an oscillatory locking member movable into and out of operative position, an oscillatory actuating member, a yielding link eccentrically connected with the actuating member and connected to said locking member, said actuating member being movable to and fro across the dead center position to vary the tension of said yielding link, and a stop for arresting the movement of said actuating member at one side of, but adjacent to, the dead center position whereby the actuating member will be held in operated position by said yielding link with the link under tension.

3. In a lock for automobile hoods and the like, a circular casing mounted in the movable wall of the hood, a revolute disk in said casing, an operating handle carried by the disk and projecting from the outer side thereof, a crank arm operatively connected with said disk, a pendant bracket arm also carried upon said movable wall, an arm pivoted to said pendant bracket arm and adapted upon oscillation to engage beneath the sill of the hood to be locked, and a helical spring connecting the crank arm and said pivoted arm.

4. In a locking device, a movable locking member, an oscillatory actuating member, an operating link connecting the actuating member and the locking member, and a housing inclosing the actuating member and link connection therewith, said housing being extended radially to form a bracket arm to which said movable locking member is connected.

5. In a locking device, an oscillatory locking arm, an oscillatory actuating member, a helical spring connecting the oscillatory actuating member and the oscillatory locking member placed under tension by the oscillation of the locking member, and a stop for the actuating member arresting said member when moved beyond a dead center position whereby the spring is maintained under tension.

6. In a locking device, a movable locking member, an oscillatory actuating member therefor, a wrist pin revolvably mounted in an eccentric position in said actuating member, a helical spring engaged with said wrist pin at one end and with the movable locking member at the opposite end and placed under tension by the rotation of the actuating member, and means for arresting the actuating member when moved beyond a dead center position.

7. In a locking device the combination

with two relatively movable members, a movable locking member carried by one of the members and engaging the other member, said locking member when in locking position being extended in angular relation to the direction of normal relative movement of said movable members, a yielding actuating connection for the locking mem-

ber and means for placing the yielding connection under tension. 10

In testimony whereof, I have hereunto set my hand this 5th day of December, 1918.

WILLIAM J. KUHLS.
